UNITED STATES PATENT OFFICE.

JAMES KNOX LOWE, GEORGE MILTON WESTGATE, AND JOHN BANKS, OF LOGAN CITY, ARIZONA TERRITORY.

MECHANICAL MOVEMENT.

SPECIFICATION forming part of Letters Patent No. 309,634, dated December 23, 1884.

Application filed September 30, 1884. (No model.)

To all whom it may concern:

Be it known that we, JAMES KNOX LOWE, GEORGE MILTON WESTGATE, and JOHN BANKS, of Logan City, in the county of Pima 5 and Territory of Arizona, have invented a new and Improved Mechanical Movement, of which the following is a full, clear, and exact description.

This invention relates to the "trammel" or 10 slotted disk movement for converting rotary into reciprocating movement; and the invention consists, principally, in such construction of the slotted disk that a small ball or circular plate may be used for bridging the cross- 15 heads across the slots.

The invention also consists of the special construction of the trammel or slotted disk, and the cross-heads and wrist-pins, all as hereinafter described and claimed.

Reference is to be had to the accompanying 20 drawings, forming part of this specification, in which similar letters of reference indicate corresponding parts in all the figures.

Figure 1 is a broken front elevation of my 25 invention. Fig. 2 is a full front elevation of the same, and Fig. 3 is a sectional plan view.

The disk or trammel A has the slots *a a* cut in it, which cross each other at right angles in the center of the trammel, and in these 30 slots are placed the cross-heads *b b*, that are pivoted to the connecting-rod B in the ordinary way. The slots *a a* reach entirely through the trammel A, and the pins *c c*, that pivot the cross-heads *b* to the rod B, reach entirely 35 through the cross-heads and the trammel and

have the small anti-friction wheels *c' c'* placed upon them, which run in the slots, and thus diminish the friction of the movement. A circular chamber, C, is formed in the center of the trammel A to receive the small ball or 40 circular plate *d*, which, as the trammel revolves, drops into the slots *a* just before the cross-heads *b* cross the intersection of the slots, so that the ball or plate *d* causes the cross-heads to cross the slots without friction and 45 without danger of binding or the pivot-pins catching in the slots.

In use the trammel A will be revolved by power applied to the shaft A', so that the rod B will receive two full reciprocations for every 50 full revolution of the trammel.

Having thus described our invention, what we claim as new, and desire to secure by Letters Patent, is—

1. The trammel A, chambered at the inter- 55 section of the slots *a* to receive a ball or disk for bridging the cross-heads across the slots, substantially as described.

2. The trammel A, chambered at C, in combination with the ball or circular plate *d* and 60 cross-heads *b*, substantially as and for the purposes set forth.

JAMES KNOX LOWE.
GEORGE MILTON WESTGATE.
JOHN BANKS.
